CLAIM

The ornamental design for a food packaging tray, as shown and described.

DESCRIPTION

FIG. 1 is a front elevation view showing our new design for a food packaging tray;

FIG. 2 is a rear elevation view of the food packaging tray design;

FIG. 3 is a right side elevation view of the food packaging tray design, the left elevation view being a mirror image thereof;

FIG. 4 is a top view of the food packaging tray design, the bottom view being a mirror image thereof;

FIG. 5 is a perspective view of the food packaging tray design, showing the front, top, and right sides thereof;

FIG. 6 is a perspective view of the food packaging tray design, showing the front, right, and bottom sides thereof;

FIG. 7 is a perspective view of the food packaging tray design, showing the rear, right, and top sides thereof; and,

FIG. 8 is a perspective view of the food packaging tray design, showing the rear, left, and bottom sides thereof.
